ANGUS ROSS BELL, OF NEW WESTMINSTER, BRITISH COLUMBIA, CANADA.

PAPER CUTTER.

Application filed May 25, 1926. Serial No. 111,644.

My invention relates to improvements in paper cutters which is particularly adapted for use in cutting desired lengths of rolls of wrapping or other paper, such as those used in retail stores and the like. The objects of my invention are to provide means whereby the end of the strip of paper forming the roll may be readily gripped and freely drawn from the roll until the desired length is attained, and then to effect a firm grip of the paper between the edge of the cutting knife and the roll, so that the strip withdrawn may be truly and effectively cut along the desired line.

The invention consists essentially of a pivotally mounted cover co-acting with a pivotally mounted knife, between which parts the paper is adapted to be drawn from the roll, as will be more fully described in the following specification, in which:—

Fig. 1 is a transverse sectional view of the invention.

Fig. 2 is a perspective view of a modified cover.

In the drawings like characters of reference indicate corresponding parts in each figure.

The numeral 1 indicates a roll of paper mounted on a shaft 2 journalled between suitable bearings. The numeral 3 indicates a casing which is adapted to be suspended from a wall 4 or other support. While I have shown the paper roll journalled within a casing, it will be obvious that such roll may be supported in a paper rack, such as is commonly used in retail stores, or in any other manner, without departing from the spirit of the invention.

The numeral 5 indicates a hinge rod extending longitudinally of the casing 3 which is preferably embedded, for the major portion of its length, in one end of the strip of metal forming the casing. The numeral 6 indicates a knife having a straight or serrated cutting edge 7, and which is provided at its opposite extremities with turned up ends 8, the rear edges of which are pivotally connected to the hinge rod 5 in a plane somewhat above the knife 6. The upper edges of the ends 8 of the knife are turned over and inwards as at 9 to define a pair of grooves 10 between them and the knife.

The numeral 11 indicates a cover for the casing which is hingedly connected thereto as at 12 and is provided at its free end

with a rod 13 extending longitudinally thereof, the ends of which are adapted to engage the grooves 10 of the knife ends 8 and to be slidable therealong. 60

When the paper roll is not enclosed within a casing I may prefer to use a skeleton cover, as shown in Figure 2, in which a hingedly mounted cover strip 14, having a rod 15 along its front edge, is adapted to 65 bear upon the strip of paper as it is led from the roll and across the knife.

Having thus described the several parts of my invention I will now briefly explain its operation. 70

The paper roll 1 is journalled between its supports, the outer edge of the knife 6 is raised as indicated by dotted lines in Figure 1, which action causes the rod 13 to slide forwardly along the grooves 10 in the knife ends 8, and the cover 11 to be raised above the rod 5 of the casing. The free end of the paper strip, forming the roll is then passed between the rod 5 of the casing 3 and the rod 13 of the cover 11 and is drawn to the outer 80 edge of the knife 6. This disposes the paper in position for use as required. When a length of paper is wanted, its free end is drawn upwards as indicated in dotted line, thus causing the cover to be lifted so that 85 the paper can be freely drawn from the roll and as the desired length is reached the free end of the strip is lowered to a position below the level of the knife 6, thus bringing the knife into a substantially horizontal position and drawing the cover downwards into gripping engagement with that transverse line of the paper which is bearing upon the rod 5 of the casing. 90

From the construction shown it will be 95 clearly seen that the grip exerted upon the paper is dependent upon the effort required to cut the paper upon the knife, so that the device can be used for cutting a light tissue or a heavy kraft paper without variation 100 of parts.

What I claim as my invention is:

1. A device of the character described comprising a paper support presenting stationary and movable clamping elements between which the paper is passed as it is drawn from the support, a cutter pivoted to said support and means slidably connecting the movable clamping element to the cutter in such manner as to separate the clamping elements on movement of the cutter in one direction and to bring said clamping ele- 110

ments into clamping relation on reverse movement of the cutter.

2. A device of the character described comprising a paper support presenting a stationary clamping element and a movable clamping element between which the paper is passed as it is drawn from the support, a cutter pivoted to said support in proximity to the stationary clamping member and providing a surface over which the paper passes from the said clamping members, said cutter being equipped with a pair of grooves, and projections carried by the movable clamping member and engaging in said grooves, the location of the grooves and projections with reference to the pivot point of the cutter being such as to cause the movable

clamping member to recede from or to approach the stationary clamping member upon swinging movement of the cutter. 20

3. A device of the character described comprising a container equipped with a hinged cover affording a movable clamping element adapted to cooperate with a stationary clamping element afforded by a wall portion of the container, a cutter hinged to said container and a means connecting the cutter and the cover whereby the latter is movable to and from the stationary clamping member in direct response to swinging 25 movement of the cutter. 30

Dated at Vancouver, B. C., this 18th day of May, 1926.

ANGUS ROSS BELL.
